UNITED STATES PATENT OFFICE.

LEANDER BECKER, OF YORK, PENNSYLVANIA; NELSON C. BAUGHMAN (ADMINISTRATOR OF SAID LEANDER BECKER, DECEASED,) ASSIGNOR TO EDWARD E. JOHNSTON, OF SAME PLACE.

WASHING-MACHINE.

SPECIFICATION forming part of Letters Patent No. 325,312, dated September 1, 1885.

Application filed March 19, 1884. (No model.)

To all whom it may concern:

Be it known that I, LEANDER BECKER, a citizen of the United States, and a resident of York, in the county of York and State of Pennsylvania, have invented certain new and useful Improvements in Washing-Machines; and I do hereby declare the following to be a full, clear, and exact description of the same, reference being had to the accompanying drawings, forming a part of this specification, and to the figures and letters of reference marked thereon.

My present invention relates to that class of washing-machines in which the clothes are subjected to the action of two co-operating rubbing-surfaces, one of which has a rotary reciprocating movement, and the other a reciprocating movement toward and from the first; and it relates particularly to improvements on the machines for which Letters Patent of the United States Nos. 217,979 and 232,667, dated July 29, 1879, and September 28, 1880, respectively, were granted me.

I will first describe at length a machine embodying my invention, and will then point out particularly the novel features in the claims at the end of this specification.

In the drawings referred to, Figure 1 represents a longitudinal vertical section of the machine; Fig. 2, a top plan view of the same with the cover or lid removed, and Fig. 3 a sectional view taken through one of the rubber-heads.

Similar letters of reference in the several figures denote the same parts.

The letter A represents the box or tub of the machine, constructed preferably in the form shown.

B is the operating-handle, consisting of two side bars or levers, b b, pivoted at their inner ends upon a cross bar, c, and united at their outer end by a cross-bar, d, as shown.

Secured rigidly to the side bars, b b, near their pivotal points, and projecting down through slots s into the tub, are two rigid metal arms, e e, of angular form, one of said arms being fastened to each of the said side bars b. The inner ends of the arms e e within the box are provided with inwardly projecting studs or pivots e' e', which enter corresponding socket

cts, f f, formed in rearward extensions of the metal head-pieces h of the rubber C. Each of the head-pieces h is provided on its inner side with flanges h' h'', and in the spaces between these flanges the ends of the slats which constitute the body of the rubber are inserted, said ends being preferably shouldered or tenoned. At the lower end of each of the heads h a third flange, h³, is provided, and serves as a stop to prevent the lower slat from slipping out. In Fig. 1 the lowest slat in the rubber C is shown extending slightly below the end of the flanged plates h; but the flange h³ on the ends of the plates is clearly shown in dotted lines in said figure.

In putting the rubber together the flanged heads are first hung upon the studs or pivots e' e', and the slats are then one after another slipped into the space or groove between the flanges h' h'' until the head is full of slats. The uppermost slat is then firmly secured by means of screws passing through openings in extensions h⁴ of the flanges h'' and into the body of said slats. By the fastening of this one slat all the rest are secured in position and need no individual fastening. Each of the heads h is further provided with a forwardly-extended arm, h⁵, having an outward bend at h⁶ and an inwardly-projecting stud or pivot, h⁷, at its forward extremity.

The larger rubber D is provided with metal heads d', of semicircular form, and having inwardly-projecting flanges d² d³ and end flanges, d⁴ d⁵. These flanges d² d³ form a semicircular recess, in which the shouldered or tenoned ends of the slats composing this rubber are confined. The relative positions of the heads are maintained by means of a cross rod or bolt, E, extending from side to side of the rubber, and connected to a bar or web of metal formed upon each of the heads, as shown. This cross-bolt has upon one end a head and upon the other a nut, and when it is tightened it not only serves to maintain the heads in their proper relative position, but also causes the slats to be tightly clamped by the heads, and thus held in place. Each of the heads d' is further provided with a pivot, d⁶, which enters a corresponding socket, d⁷, secured to the inner side of the tub, and also with a pro-

jecting arm, d^6 , terminating in a socket which fits the stud or pivot h^7 of the arm h^5 of the rubber C.

From the description of the various parts 5 above given the operation of the machine will be readily understood.

A sufficient quantity of water having been placed in the tub, the handle is raised, as shown in Fig. 1, and the fabrics to be washed 10 are thrown in between the rubbers C and D. The handle is then worked down and up, and imparts a forward and backward and slight oscillatory movement to the rubber C and a reciprocating circular motion to the rubber D, 15 the coming together of the rubbers causing the water to be forced up between them, and the fabrics to be also carried up between them and subjected to a thorough cleansing. The rubber D, it will be observed, is hung somewhat eccentrically upon its pivots, and rises 20 and falls in its circular movement.

It will also be noticed that only the rubber D is required to have a bearing upon the inner walls of the box or tub, the rubber C being entirely supported upon the arms e^e . The slats of the rubbers are preferably formed so 25 as to present a corrugated surface, and are perforated to permit the passage through them of the water squeezed out of the fabric, as 30 shown.

Having thus described my invention, I claim as new—

1. The combination, with the tub or box, of the vibrating handle, the arms extending down into the box, the rubber hung by a pivotal connection upon said arms, and the other rubber pivoted to the sides of the box and connected to the first-named rubber by the arms, whereby when the handle is operated a back-and-forth and slightly oscillatory motion is given the first-mentioned rubber, and a reciprocating circular motion is given the other rubber, substantially as described. 35

2. The combination, with the tub, of the vibrating handle, the arms connected to the handle and extended down into the tub, the rubber C, having the rear sockets on its heads for receiving the pivots of the levers, and having the forwardly-extended arms, and the rubber D, having its heads pivoted to the sides 40 of the box, and having the socketed arms, with which the forwardly-extended arms of the rubber C are connected by a jointed connection, substantially as described. 45 50

LEANDER BECKER.
